UNITED STATES PATENT OFFICE.

IVAN D. THORNBURGH, OF BERKELEY, CALIFORNIA, ASSIGNOR TO AMERICAN CAN COMPANY, OF SAN FRANCISCO, CALIFORNIA, A CORPORATION OF NEW JERSEY.

ORGANIZED APPARATUS FOR LINING CAN ENDS AND SEAMING SAME TO CAN BODIES.

Application filed June 28, 1917. Serial No. 177,499.

To all whom it may concern:

Be it known that I, IVAN D. THORNBURGH, a citizen of the United States, residing at Berkeley, in the county of Alameda and State of California, have invented certain new and useful Improvements in Organized Apparatus for Lining Can Ends and Seaming Same to Can Bodies, of which the following is a specification.

10 The present invention relates to an organized apparatus for cutting gasket ring liners from blanks or from a web of liner material, positioning said liners within the flanges of can ends, and applying and seaming said can ends to can bodies.

The object of the invention is to provide a machine for the described purpose, in which a can end is lined, applied and seamed to a can body, all the operations incident thereto being automatically performed by the various inter-working parts of the machine. By the use of this apparatus the canner or can maker, as the case may be, is enabled to line can ends, properly position the same relative to can bodies and permanently unite the lined can ends with the can bodies by means of one organized machine. The various operations of cutting the gasket liner from liner material and applying the same to the can end, positioning the lined can end relative to a can body, and seaming the same thereto, which have heretofore required individual machines, can now be performed under the present invention by a single organized machine. By thus combining the operations of a number of machines into one interconnected apparatus, a considerable reduction in expense and in the amount of labor required for these operations is secured, inasmuch as one operator can easily handle the complete machine. In addition a saving in space and in first cost is also effected.

The invention will be hereinafter described and is herewith illustrated in its preferred form, but I do not wish to be understood as limiting myself thereto, for the reason that many changes may be made in

the form and construction of the machine without departing from the spirit of the invention, and it is therefore my wish to claim the invention as broadly as the state of the art will permit. 50

In order to comprehend the invention, reference should be had to the accompanying sheets of drawings, wherein, 55

Fig. 1 is a front elevation of the complete machine.

Fig. 2 is a sectional plan view taken on the line 2—2 of Fig. 1. 60

Fig. 3 is a sectional elevation taken in two planes represented by the lines 3—3 of Figs. 1 and 2, and viewed in the direction of the arrows.

Fig. 4 is a sectional elevation taken on the line 4—4 of Fig. 1 and viewed in the direction of the arrows. 65

Fig. 5 is a detailed sectional elevation taken on the line 5—5 of Fig. 1 and viewed in the direction of the arrows. 70

Fig. 6 is a detailed sectional elevation taken on the line 6—6 of Fig. 1 and viewed in the direction of the arrows.

Fig. 7 is a detailed sectional plan of a portion of the machine, showing an arrangement for utilizing a continuous web of liner material for the cutting therefrom of the ring liners. 75

Fig. 8 is a vertical detail, enlarged, of the liner cutting dies employed for severing the ring liners from a web of liner material. 80

Fig. 9 is an enlarged detailed sectional elevation illustrating the apertured plate for supporting the lined can end relative to the flanged can body positioned at the seaming station, disclosing the rotatable support for the can body and the chuck for clamping the can end to the can body during the seaming operations. 85

The frame of the machine, as shown in Fig. 1 of the drawings, comprises upright end members 1, connected together by transverse webs 2 and 3 and a lower cross member 4, and carrying a horizontally disposed bed or table having an elevated portion 5 and a depressed portion 6. 90 95

The various working parts of the machine are operated from a horizontal drive shaft 7 journalled in the upper portion of the upright frame members 1, and carrying 5 at one end a pulley 8 adapted to receive power from any desired source, not shown. The other end of said drive shaft is connected, by means of a pair of miter gears 9, with a vertically disposed shaft 10 carried 10 in suitable brackets 11, and said vertical shaft is in turn connected, by means of a pair of miter gears 12, with a lower horizontal shaft 13 journalled in the lower portion of the frame uprights 1. 15 A horizontal turret 14, Figs. 1, 2, and 3 of the drawings, is mounted above the upper table 5 and is carried by a vertically disposed shaft 15, suitably journalled in said table and the lower cross frame member 4. 20 Said shaft is intermittently rotated by means of a mutilated worm 16, Figs. 1 and 3 of the drawings, mounted upon the lower horizontal shaft 13, and adapted to mesh with a correspondingly formed worm wheel 25 17 carried by said turret shaft. The turret 14 is formed with a number of evenly disposed spaced apertures 18, Fig. 2 of the drawings, each being formed with two annular shoulders 19 and 20, Fig. 3 of the 30 drawings, the former of a diameter to receive a can end and the latter of a diameter to receive a gasket liner for said end. Radial grooves 21, Figs. 1 and 2 of the drawings, are formed in the upper face of said turret, 35 extending from the apertures 18 to the outer edge thereof, and each of said grooves is formed with a depressed portion 22 at its center.

A magazine or holder, adapted to contain 40 a stack of blanks when the ring liners are to be cut from previously formed blanks, is mounted upon a bracket extended rearwardly from the table 5 at the rear of the turret 14. As shown in Figs. 2 and 3 of the drawings, the magazine comprises four spaced vertically disposed rods 23 arising from a bracket 24 and adapted to contain a stack of liner blanks 25. The lowermost liner blank 25' of said stack is removed from the 50 bottom of the holder by means of a suitably formed knife 26, Fig. 3 of the drawings, carried by a feed slide 27, the latter being mounted in suitably formed horizontal guides 28 and operated by means of a link 55 29 and a bell-crank lever 30, the latter receiving its motion in a manner to be presently described.

The knife 26 of the feed slide 27 engages 60 the lowermost liner blank 25' of the stack 25 and pushes the same forwardly through the radial groove 21 in the turret 14 into the aperture 18 thereof, where said liner blank rests upon the lower shoulder 20. During this movement of the feed slide 27, 65 the knife 26 thereof operates within the de-

pressed portion of said radial turret groove 21.

It is understood that during this forward movement of the feed slide 27 to place the liner blank 25' upon the annular shoulder 20 70 of the turret aperture 18, the turret 14 remains stationary. Immediately upon the withdrawal of said feed slide to free its knife 26 from the turret, said turret is advanced one step in its rotation by the described mechanism, thereby carrying the liner blank from the position A, Fig. 2 of the drawings, to the position B. At this position the liner blank, resting within the shouldered aperture of the turret, is in 80 alignment with a pair of oppositely reciprocating liner cutting dies adapted to cut a ring liner from said blank, Figs. 3 and 8 of the drawings.

Upper and lower die heads 31 and 32 85 respectively are mounted within suitably formed guides 33 and 35 and are operated by means of cranks 36 and 37, respectively carried by the upper and lower horizontal shafts 7 and 13, said cranks being connected with 90 said die heads by adjustable connecting rods 38 and 39. The die heads 31 and 32 are offset as shown, and carry on their adjacent ends co-acting die members. The lower head 32 carries an annular ring die 40, the interior thereof, and also the interior of said head, being hollow to permit the discharge of the waste from the web or blank. The upper head 31 carries a central die 41, surrounded by a stripper ring 42, which is normally held, in a position to allow its edge 95 to project beyond said die, by springs 43. It will be readily understood that when said dies come together, a ring is cut from the outer edge of the liner blank by means of 100 the co-acting dies 40 and 41, the waste core of said blank being forced through the hollow lower die 40 by the upper die 41. Upon the separation of said dies the ring liner is stripped from the upper die 41 by 110 the action of the stripper ring 42, and is allowed to rest upon the shoulder 20 of the 115 turret aperture 18.

The operating lever 30 of the feed slide 27 is connected with the lower die head 32 by means of a link 30', as shown, so that said feed slide is operated, to place a liner blank 25' within a turret aperture 18 at the position A, by the movement of said die head 32, which movement also causes a ring liner to 120 be cut from the previous blank at the position B.

The turret 14, after said dies have been separated, is advanced one step to bring the aperture 18, with the cut ring liner resting 125 therein, into the position C, Fig. 2 of the drawings. At this position the ring liner is not acted upon, but merely rests during the cutting of a second liner and the positioning of a third blank upon the turret. The third 130

advance movement of the turret 14 brings the cut ring liner to the position D, at which it is axially aligned beneath a holder containing a stack of can ends.

5 As shown in Figs. 2 and 3 of the drawings, said can end holder comprises four vertical rods 45 arising from an annular base 46, the latter being carried by a forwardly extending bracket 47. The stack of can ends 48 10 within said holder is normally supported by a pair of oppositely disposed cut-out arms 49, Fig. 2 of the drawings, carrying fingers 50 projecting from opposite sides into the annular base 46 of said holder. Said stack 15 of ends 48 is shown in Fig. 3 of the drawings, but is omitted from Fig. 2 for clearness. Said cut-out arms 49 are pivotally mounted at 51, Fig. 2 of the drawings, and are inter-connected by means of gear teeth 20 52 to operate in unison and in opposite directions. One of said arms carries a projecting lever 53 which is connected by means of a rod 54 with a crank 55 mounted upon the upper end of a vertically disposed shaft 25 56. Said shaft, as shown in Figs. 1 and 4 of the drawings, is journalled in the table 5 and in the web 3 and carries upon its lower end a crank 57 connected with a yoke 58 positioned to straddle the lower drive shaft 30 13, and carrying a cam following roller 59, Fig. 4 of the drawings, adapted to follow an eccentric groove 60 formed in the face of a cam member 61 mounted upon said shaft 13. Thus at each revolution of said shaft 35 13 the vertical shaft 56 is oscillated to swing the can end feed cut-out arms 49 to release the stack of can ends 48 within the holder and to allow said stack to drop until the lowermost end 48' rests upon the upper annular shoulder 19 of the turret aperture 18. Said cut out arms are then brought together, the fingers 50 thereof being interposed between the lowermost can end 48' and the end next above, and thereby raising the stack 40 45 of ends to free said lowermost end therefrom.

The turret aperture 18 now contains a ring liner 44, resting upon the lower annular shoulder 20, and a cam end 48', resting upon the upper annular shoulder 19. Said turret is then advanced one step to bring said liner and can end to the position E, Figs. 2 and 5 of the drawings, at which said liner and end are assembled. As shown 55 in Fig. 5, the table 5 carries a vertically slideable assembling head 62, positioned in alignment beneath the turret aperture 18 at said position E. This head is carried upon a sliding rod 63, mounted within a suitable guide 64 and secure to one arm of a T-head 65 beneath said table, said T-head being carried on the upper end of a vertical sliding rod 66, Figs. 1 and 5 of the drawings, the latter being mounted in a suitable 60 65 guide attached to the web 3 and connected at its lower end with one arm of a bell-crank lever 67, whose other arm carries a cam following roller 68 adapted to lie within and follow an eccentric groove 69 formed in the face of a cam member 70 mounted upon the lower transverse shaft 13. The assembling head 62 is formed with an upwardly projecting annular flange 62', Fig. 5 of the drawings, adapted to engage the ring liner 44 resting upon the shoulder 20 and to force the same up into the flange of the can end 48' resting upon the upper annular shoulder 19. The outer edge of the flange of said can end is understood to be inwardly curled in the usual manner to retain the ring liner 80 therein after the removal of the head 62.

The can end 48', with the ring liner 44 placed in the flange thereof, is then carried, by the next movement of the turret 14, to the position F, at which it is automatically removed from said turret and transferred to the seaming mechanism. For removing said lined can end from said turret there is provided a vertically slideable plunger head 71, Fig. 5 of the drawings carried upon the upper end of a sliding rod 72, mounted in a suitable guide 73 beneath the table 5, said rod being carried by the T-shaped head 65. The plunger head 71 operates through the turret aperture 18 and lifts the lined can end out of the said aperture, through an aperture 74 in a fixed plate 75 positioned above the turret 14. In this position the lined can end is engaged by a swinging transfer arm 76, Fig. 2 of the drawings, mounted upon the upper end of the vertical oscillating shaft 56, and adapted to push said lined can end through an arcuate guide-way formed by the fixed plate 75 and a superposed plate 77 spaced thereabove, Figs. 100 105 2 and 5 of the drawings. This movement of the transfer arm 76 carries the lined can end 48' from within the guide-way formed by the plates 75 and 77, and deposits the said end within the shouldered seat *a* of an apertured plate 77', which plate may be said to constitute a continuation of the fixed plate 75. As thus positioned the lined can end is held above and in axial alignment with a can body at the position G.

A second turret 78, Figs. 1, 2, 4, and 6 of the drawings, having can receiving pockets 79 Fig. 2, formed in its periphery, is positioned above the lower table 6 and is carried by the upper end of a vertical shaft 79', Fig. 6, journalled in said table and the frame web 3 and driven by means of a pair of spur gears 80 and 81, an idler shaft 82 Figs. 1 and 6, and a train of gears 83, 84 and 85, Fig. 1, the latter mounted upon the vertical turret shaft 15. The can bodies 86 are brought into the machine between suitable spaced guide rails 87 upon a belt 88, Figs. 1 and 2 of the drawings, and are placed thereby within the pockets 79 of the turret 120 125 130

78, by which said can bodies are advanced within the curved guide rail 89 from the position H to the position G, Fig. 2.

At said position G, as before stated, the 5 lined can end 48' is placed above and in axial alignment with, and is held by the said apertured plate 77' spaced a slight distance from the flanged end of the positioned can body 86, Fig. 9 of the drawings. By 10 means of the hereinafter described means the can body is lifted through the aperture a' of the plate 77' to engage with the can end and with the end thus held raised to the seaming mechanism for permanently 15 uniting the lined can end to the can body, by the usual seaming process. For this purpose, a seaming head 90 is provided, as shown in Figs. 1 and 2 of the drawings, and is carried upon the lower end of a vertical 20 oscillating shaft 91, suitably journaled in the upper frame web, 2 and provided at its upper end with a crank 92 connected by a link 93, Figs. 1 and 4 with one arm of a bell-crank lever 94 whose other arm carries 25 a cam following roller 95 adapted to be actuated by a grooved cam 96 mounted upon the upper drive shaft 7. The seaming head 90 is provided with a pair of seaming rolls 98 and 99, Figs. 2 and 4 of the drawings, 30 adapted to be brought successively into engagement with the flange of the can end by the oscillation of said head and its shaft.

At the position G the can body rests upon a rotatable plate 100, Fig. 4 of the drawings, 35 mounted upon a vertically slidable plunger 101, the latter being carried by a downwardly extending rod 102, whose lower end carries a cam following roller 103 adapted to lie within an eccentric groove 104, formed in 40 a cam member 105 mounted upon the lower horizontal shaft 13. By means of this mechanism, the can body is raised through the aperture a' of the plate 77' to first bring its flanged end into engagement with the 45 lined can end and then by its continued upward movement to place the said end against a rotary chuck 106, Fig. 4 of the drawings, carried upon the lower end of a continuously 50 rotating spindle 107, driven by bevel gears 108 and 109, Fig. 1 of the drawings, from the upper horizontal shaft 7. The can with 55 its lined end in the position G clamped to the chuck 106 is thus rotated at a high rate of speed by said chuck 106, and the seaming rolls 98 and 99 are successively brought into engagement with the flange of the can end to curl and seam the same over the flange of the can body to make a permanent tight seal in the usual well-known manner.

60 After the completion of the seaming operation the diameter of the seamed end of the can body is slightly less than the diameter of the aperture a', so that with the lowering movement of the plunger 101 the 65 seamed end of the can body passes through

the aperture a' to place the can body beneath the plate 77', at which time the turret 78 is advanced one step to bring the seamed can and its end to the position I Fig. 2 of the drawings, and at the next step movement 70 of said turret said can is discharged therefrom between the spaced guide rails 110 and 111.

For operating the can body feed belt 88 I have shown a shaft 112, Figs. 1 and 6 of the drawings, upon which the end pulley 113 of said belt is fixed, and said shaft is continuously driven by means of spiral gears 114 and 115, Fig. 1, the latter being mounted upon the vertical shaft 10. 80

I have provided in a modified form of the present invention, mechanism for forming ring liners from a continuous strip or web of liner material, in place of the disk blanks utilized in the form described above. 85 In this modified form, illustrated in Figs. 7 and 8 of the drawings, a web or strip of liner material 116 is carried by any convenient means not shown, and is directed across immediately above the turret 14 by 90 means of guides 117, so that it overlies one of the apertures 18 of said turret at the position B. Beneath the web and above the turret is placed a stationary die ring 118, mounted upon one of the upright frame 95 members 1, and provided with an opening axially aligned with said aperture 18 at the position B. An apertured guide or stripper plate 119 is also provided above the web of liner material to retain the same in position. 100

The ring liner is cut by the dies 40 and 41 substantially as in the previously described mechanism. In the modified form however, the stripper ring 42 of the upper die 41 stamps out a disk blank by being introduced 105 through the stationary die ring 118, and the disk thus formed is carried downward into the aperture 18 of the turret and is there clamped at its edge between said stripper ring 42 and lower die ring 40. The upper 110 die 41 continues to move downwardly into the lower die ring 40 to stamp out a waste blank or core and to thus form the ring liner. The dies are then drawn apart, the lower die moving out of the aperture 18 and 115 the upper die moving upwardly to clear the web 116.

The web of liner material is advanced by means of a pair of rollers 120, between which it is passed, and one of said rollers is driven 120 by means of gears 121 and 122, the latter being intermittently rotated by means of a ratchet mechanism 123. A connecting rod 124, attached to the strap of an eccentric 125 mounted upon the end of the lower horizontal shaft 13, operates the ratchet 123. A spring 126 is provided to retain the ratchet mechanism in driving relation. Thus at each revolution of the drive shaft, and after each ring liner has been formed, the web is 130

advanced one step to provide a new place for the stamping of the next liner. In this form of mechanism the liner is cut and positioned upon the turret at the position B, no action 5 taking place at either A or C.

The operation of the complete machine may be briefly described as follows:

In the preferred form of the apparatus, a liner blank 25' is placed upon the lower 10 shoulder 20 of one of the apertures 18 of the turret 14 at the position A, Fig. 2 of the drawings, and is carried by the step movement of said turret to the position B, at which the waste core is cut from the blank 15 by means of the oppositely operating co-acting dies 40 and 41, Fig. 3, and the ring liner is left resting upon the flange 20 of the turret aperture. If the cutting of the ring liner is from a continuous web of liner mate- 20 rial, the ring liner is cut from said web of liner material at the position B and is placed immediately upon the flange 20 of the turret aperture 18 in the manner above de- scribed. From this point on the operation 25 is identical in either case.

Two successive step movements of the turret 14 carry the ring liner to the position D, Fig. 2 of the drawings, at which it is axially aligned beneath the stack of can ends 30 within the holder 45. During the period of rest of the turret with the liner in the position D, the lowermost can end 48' is cut out from the bottom of the stack by the swinging arms 49 and is allowed to rest upon the 35 upper shoulder 19 of the turret aperture 18. The lined can end and ring liner are then carried by the fourth step movement of the turret 14 to the position E, at which the plunger 62, Fig. 5 of the drawings, is ele- 40 vated to force the liner into the flange of the can end. The lined can end, still resting upon the flange 19 of the turret aperture 18, is then carried to the position F, where it is elevated by the plunger 71 and engaged 45 by the swinging transfer arm 76, and is thereby transferred from the turret 14 and placed into the seat *a* of the apertured plate 77' and supported thereby above a can body at the position G.

The can body has previously been brought 50 into the machine by the belt 88, and engaged by the can body turret 78 and moved thereby to the position G to stand in axial alignment with the lined positioned can end. The can 55 body is then moved through the aperture *a'* of the plate 77' into engagement with the lined can end by an upward movement of the plunger 101, the continued movement there- 60 of placing the lined end carried by the can body against the chuck 106, by which the can body and its loosely applied lined end are rapidly rotated. During this rotation of the can the seaming rolls 98 and 99 are suc- 65 cessively brought into engagement with the flange of the can end to curl the same over

the flange of the can body to form a tight seam. After this operation is completed, the seamed can is lowered beneath the apertured plate 77' and moved onward and discharged in the manner previously described. 70

It is to be noted that the operation of the various parts of the machine is entirely automatic. A supply of liner blanks is held within the holder 23, a supply of can ends 75 within the holder 45, and the can bodies are brought in by the belt 88. The ring liners are formed from the blanks and placed with in the flanges of the can ends, and the lined ends are loosely positioned upon the can bodies and secured thereto, entirely by automatically operated means, so that one operator can easily handle the complete machine, the only attention required being the replen- 80 ishing of the supplies of liner blanks and can ends within their respective magazines. 85

Having thus described the invention what is claimed as new and desired to be protected by Letters Patent is:

1. In a machine having means for applying can ends to can bodies, the combination 90 therewith of cooperating mechanism for forming from suitable material ring liners for said can ends, and means for inserting such ring liners in the can ends before they are applied to the can bodies. 95

2. In a machine having means for applying can ends to can bodies, the combination therewith of cooperating mechanism and dies for cutting from sheet material ring liners for said can ends, and means for inserting such ring liners in the can ends before they are applied to the can bodies. 100

3. In a machine having means for applying can ends to can bodies at an applying station, the combination therewith of means 105 for feeding can bodies to said applying station, means for feeding can ends to said applying station, means for forming ring liners from flat material, means for inserting the formed liners in the said can ends while they are under the control of said can end feeding means, and mechanism for actuating all of said instrumentalities in timed relation. 110

4. An organized apparatus for the de- 115 scribed purpose, comprising carrier mechanism, means for forming a ring liner and placing the same upon said carrier mechanism, means for positioning a flanged can end upon said carrier mechanism in axial alignment with the ring liner thereon, means 120 for applying said ring liner to the flange of said can end, means for removing the lined can end from said carrier mechanism and placing the same in axial alignment with a positioned can body, means for hermetically 125 sealing said can end upon said can body and mechanism for actuating said mentioned parts in timed relation.

5. An organized apparatus for the de- 130 scribed purpose comprising a rotary carrier,

- means for forming a ring liner and placing the same upon said carrier, a holder adapted to contain a supply of flanged can ends, mechanism for moving said carrier to convey said ring liner into position for axial alignment with a flanged can end, means for removing said can end from said holder and placing the same upon said carrier above the ring liner, means for applying said ring liner to the flange of said can end, means for removing the lined can end from said carrier and placing the same in spaced relation above a positioned can body, vertically movable means for assembling the can body and lined end, devices for hermetically sealing said end upon said body, and mechanism for actuating said parts in timed relation.
6. An organized apparatus for the described purpose, the same comprising means for forming a ring liner, means for applying the same to the flange of a can end, means for positioning a can body to receive said lined end, means for loosely placing said lined can end upon said can body, devices for hermetically sealing said can end upon said can body, and mechanism for actuating said mentioned parts in timed relation.
7. An organized apparatus for the described purpose, the same comprising a holder adapted to contain a supply of disk blanks, means for removing a blank from said holder, cutting means for forming a ring liner therefrom, means for transferring the said liner from the cutting means and positioning the same for axial alignment with a can end, devices for positioning a flanged can end above the said ring liner, means for applying said ring liner to the flange of said positioned can end, means for loosely applying the lined can end upon a positioned can body, and moving the assembled parts to seaming position, mechanism for hermetically sealing said can end upon said can body, and interconnected means for actuating the foregoing in timed relation.
8. An organized apparatus for the described purpose, the same comprising a holder adapted to contain a supply of disk blanks, means for removing a blank from said holder and forming a ring liner therefrom, a second holder adapted to contain a supply of flanged can ends, means for removing a can end from said second holder and positioning the same above and in alignment with said ring liner, mechanism for applying said liner to the flange of said can end, means for placing the lined can end above and in axial alignment with a positioned can body, and devices for moving the can body into engagement with the can end and carrying the assembled parts within the sphere of seaming mechanism, mechanism for sealing said can end upon said can body and interconnected means for actuating the foregoing in timed relation.

9. An organized apparatus for the described purpose, the same comprising conveying means for placing a disk blank upon said conveying means, means for forming a ring liner from said disk blank, means for placing a flanged can end upon said conveying means above and in axial alignment with said ring liner, means for applying said ring liner to the flange of said can end, mechanism for positioning a can body in axial alignment with the lined can end, devices for hermetically sealing said can end upon said can body, and interconnected mechanism for actuating said parts in timed relation.

10. An organized apparatus for the described purpose, the same comprising conveying means, a holder adapted to contain a supply of disk blanks, reciprocating means for removing a blank from said holder and placing the same upon said conveying means, means for forming a ring liner from said blank, a holder adapted to contain a supply of flanged can ends, reciprocating means for removing a can end from said holder and placing the same upon said conveying means above and in axial alignment with said ring liner, means for applying said ring liner to the flange of said can end, mechanism for positioning a can body in axial alignment with the lined can end, devices for moving the can body into clamped engagement with the lined can end, mechanism for hermetically sealing said can end upon said can body and interconnected working instrumentalities for actuating said parts in timed relation.

11. An organized apparatus for the described purpose, the same comprising a rotatable turret, means for forming a ring liner from flat liner material and placing the same upon said turret, means for positioning a flanged can end upon said turret above and in axial alignment with said ring liner, means for applying said ring liner to the flange of said can end, mechanism for removing the lined can end from said turret and placing the same above and in axial alignment with a positioned can body, devices for hermetically sealing said can end upon said can body and interconnected working instrumentalities for actuating said parts in timed relation.

12. In an organized apparatus for the described purpose, the combination with means for cutting and applying a ring liner to a flanged can end, feed means for placing a can body in vertical position at an assembling station, mechanism for transferring the lined can end to the assembling station and in superposed axial alignment with the can body, a rotatable can chuck, devices for raising the can body into assembled engagement with the can end and clamping the assembling parts to the can chuck, and mechanism for seaming the flange of the can end.

to the can body when the parts are in raised position.

13. In an organized apparatus for the described purpose, the combination of mechanism for placing a can body and a lined flanged can end in axial alinement at an assembling station with the can end in superposed relation to the can body, devices for raising the can body and clamping the can end to said can body, means for imparting rotation to the clamping devices and to the can body and end clamped therebetween, mechanism for seaming the flange of the can end to the can body while the said parts are held in clamped position, cooperating means for lining said can end before it is alined with the can body, and actuating mechanism connected with the can body and can end positioning means and with said devices for raising the can body and clamping the same and the can end and with said means for imparting rotation to the clamping devices, and with said mechanism for seaming the flange and with said can end lining means, and operating all of said elements automatically in timed relation.

14. A combination with mechanism for cutting a ring liner from flat liner material and applying the same to a flanged can end, mechanism for moving said lined can end to assembling position, means for positioning a can body at said assembling station for axial alignment with a lined can end, devices for assembling the can body with the can end and holding the same so assembled during seaming operation, and mechanism for double seaming the flange of the can end to the can body.

15. In an apparatus for the described purpose, the combination of mechanism for feeding a flanged can body to an assembling station, means for positioning a lined flanged can end above and in axial alinement with said can body, devices for assembling the can body with the can end and holding the same so assembled during a seaming operation, mechanism for double seaming the flanged can end to the can body while the parts are held in assembled position, cooperating means for lining said can end before it is so positioned in alinement with the can body, and actuating mechanism connected with said feeding mechanism and with said positioning means and with said assembling and holding devices and with said double seaming mechanism and with said lining means, and operating all of said elements automatically in timed relation.

16. In an apparatus for the described purpose, the combination of an apertured plate provided with a recessed shouldered seat, means for positioning a lined flanged can end within the shouldered seat of said apertured plate, rotary means for placing a can body beneath said plate for axial aline-

ment with said can end, a can chuck, vertically movable means for moving said can body through said apertured plate into assembling engagement with a positioned can end and for lifting the assembled parts into clamped engagement with said can chuck, means associated therewith for double seaming the flanged can end to the can body while held clamped to the said chuck, cooperating means for lining said can end before it is so positioned in said plate, and actuating mechanism connected with said positioning means and with said rotary means and with said vertically movable means and with said double seaming means and with said lining means for operating all of said elements automatically in timed relation.

17. An apparatus for the described purpose having, in combination, mechanism for moving a flanged can body into position for axial alinement with a flanged lined can end, means for positioning a lined flanged can end in superposed axial alinement with said positioned can body, devices for assembling the can body and end and holding the same assembled during a seaming operation, mechanism for double seaming the flange of the can end to the can body while so held, cooperating means for lining said can end before it is so positioned in said plate, actuating mechanism connected with said positioning means and with said rotary means and with said vertically movable means and with said double seaming means and with said lining means and operating all of said elements automatically in timed relation.

18. An apparatus for the described purpose, the combination with mechanism for cutting a ring liner from flat liner material and depositing the same within an orifice of a rotary carrier, means for positioning a flanged can end in an orifice of said carrier and in superposed axial alignment with said ring liner, devices for assembling the liner relative to the flanged can end, means for transferring the lined can end to an assembling station, mechanism for placing a can body at said station in a position below and for axial alignment with the lined can end transferred to said station, devices for moving the can body into engagement with the positioned can end and holding the end clamped thereto during a seaming operation, and mechanism for double seaming the flange of the can end to the can body while the members are held clamped one to the other.

19. In an apparatus for the described purpose, the combination with inter-connected instrumentalities operated in timed relation for successively cutting ring liners from flat liner material and positioning a flanged can end in axial alinement with said liner, assembling the liner relative to the flange of the can end and transferring the said lined

end to an assembling position, means for positioning a flanged can body for axial alignment with said can end, devices for moving the can body into engagement with the can end and carrying the assembled members in unison within the sphere of seaming mechanism, and mechanism for double seaming the flange of the can end to the can body while the parts are held in assembled relation.

20. An apparatus for the described purpose, having in combination, instrumentalities for successively delivering flanged can bodies and lined flanged can ends in axial alignment to an assembling station with the can end in superposed relation to the can body, a rotary can chuck situated at said station above and in axial alignment with the can end there positioned, devices for moving the can body into engagement with the can end and clamping said members to the rotary can chuck, and so holding the same during a sealing operation, mechanism situated adjacent the can chuck for double seaming the flange of the can end to the can body while the said parts are held clamped to the can chuck, cooperating means for lining said can end before the same is clamped with the can body, and actuating mechanism connected with said delivering instrumentalities and with said can chuck and with said devices for moving and holding the can body and with said double seaming mechanism and with said lining means, for operating all of said elements automatically in timed relation.

21. An organized apparatus for the described purpose, the same comprising associated instrumentalities for cutting a gasket ring liner from flat liner material and positioning the same for axial alignment with a flanged can end, placing a flanged can end in superposed axial alignment with said ring liner and assembling the liner relative to the flanged can end, means for transferring the lined can end to an assembling station, interconnected means for positioning a flanged can body at said station for axial alignment with a lined can end supported thereabove, devices for moving the can body into engagement with the can end and holding the same thereto during a sealing operation, and mechanism for double seaming the flange of the can end to the can body while the members are held one to the other.

22. An organized apparatus for the described purpose, having in combination, means for positioning a can body to an assembling station, means associated therewith for positioning a lined flanged can end in axial alignment with said can body and in superposed relation therewith, devices for assembling the can body with the can end and for moving the parts thus assembled to seaming position, mechanism for double

seaming the flange of the can end to the can body while the parts are so held, cooperating means for lining the can end before the can end and body are assembled, and actuating mechanism connected with said positioning means and with said assembling and moving devices and with said double seaming mechanism and with said lining means, for operating all of said elements automatically in timed relation.

23. In a machine of the character described, the combination of dies for cutting packing material to produce a packing ring, means for feeding an unlined can end to an assembling station, means for feeding a cut ring liner from said dies to said station, mechanism for assembling said produced ring liner and can end ready to be applied to close a can, means for feeding an unclosed can to a seaming station, devices for feeding the lined can end to said seaming station, means for applying the lined can end to said can, attaching means for uniting the same with the can, and actuating mechanism for moving said ring liner cutting dies and attaching means in timed relation for said purposes, and for moving the intermediate instrumentalities as described.

24. In a machine of the character described, the combination of dies for cutting packing material to produce a packing ring, means for feeding an unlined can end to an assembling station, means for feeding a cut ring liner from said dies to said station comprising an apertured member adapted to receive and carry said ring liner and can end, mechanism for assembling said produced ring liner and can end ready to be applied to close a can, means for feeding an unclosed can to a seaming station, devices for feeding the lined can end from said apertured member to said seaming station, means for applying the lined can end to said can, attaching means for uniting the same with the can, and actuating mechanism for moving said ring liner cutting dies and attaching means in timed relation for said purposes, and for moving the intermediate instrumentalities as described.

25. In a machine of the character described, the combination of dies for cutting packing material to produce a packing ring, means for feeding an unlined can end to an assembling station, means for feeding a cut ring liner from said dies to said station comprising an apertured member the aperture of which is provided with a lower shoulder for supporting a can end and an upper shoulder for supporting a cut ring liner, mechanism for assembling said produced ring liner and can end ready to be applied to close a can, means for feeding an unclosed can to a seaming station, devices for feeding the lined can end to said seaming station, means for applying the lined can

end to said can, attaching means for uniting the same with the can, and actuating mechanism for moving said ring liner cutting dies and attaching means in timed relation for said purposes, and for moving the intermediate instrumentalities as described.

5 In testimony whereof I have signed my

name to this specification in the presence of two subscribing witnesses.

IVAN D. THORNBURGH.
